UNITED STATES PATENT OFFICE.

BARNEY GREENWOOD, OF CHICAGO, ILLINOIS.

POCKET.

1,091,927.

Specification of Letters Patent. Patented Mar. 31, 1914.

Application filed July 5, 1912. Serial No. 707,705.

To all whom it may concern:

Be it known that I, BARNEY GREENWOOD, a citizen of the United States, residing at Chicago, in the county of Cook and State 5 of Illinois, have invented a new and useful Improvement in Pockets, of which the following is a specification.

My invention relates to wearing apparel and particularly to an improvement in the 10 construction in conjunction with an ordinary pocket.

One object of the invention is to provide a plurality of cigar holding compartments each adapted to snugly hold and protect one 15 cigar.

Another object is to provide such compartments by subdividing a supplemental pocket which is superposed on a main pocket.

The invention will be clearly understood 20 by referring to the accompanying drawing in which the figure is a front view showing the pocket arrangement.

The cloth 5 has the upper and lower slits 6 and 8 therein which constitute openings or

mouths for the main and supplemental 25 pockets 7 and 9 respectively. The supplemental pocket is subdivided by stitchings 10 into compartments 9' each of a size to snugly receive one cigar. This supplemental pocket will not interfere with the free use of the 30 main pocket, and the contents of the compartments will be protected in great part by the main pocket and the cloth 5.

I claim the following:

In wearing apparel, the cloth 5 having the 35 upper and lower slits and the main and supplemental pockets 7 and 9 respectively for which said slits form mouths, the supplemental pocket being between the cloth 5 and the main pocket and subdivided into com- 40 partments by stitchings 10.

In witness whereof I have signed my name to the foregoing specification in the presence of two subscribing witnesses.

BARNEY GREENWOOD.
